UNITED STATES PATENT OFFICE.

ABRAHAM R. MIRANDA, OF BOSTON, MASSACHUSETTS.

GARBAGE-BUCKET.

SPECIFICATION forming part of Letters Patent No. 499,137, dated June 6, 1893.

Application filed September 15, 1892. Serial No. 445,993. (No model.)

To all whom it may concern:

Be it known that I, ABRAHAM R. MIRANDA, a citizen of the United States of America, and a resident of the city of Boston, in the county 5 of Suffolk and State of Massachusetts, have invented a certain new and useful Improved Sanitary Garbage-Bucket, of which the following is a full, clear, and exact description.

This invention consists of a cabinet, substantially as hereinafter described, to receive 10 a bucket or pail, suitable for holding garbage, &c., and by means of which, with the cabinet closed, the garbage, &c., may be disinfected and its obnoxious gases destroyed, 15 or in other words, neutralized.

In the drawings, forming part of this specification, Figure 1 is a plan view of the cabinet closed. Fig. 2 is a central vertical section, line 2—2, Fig. 1. Fig. 3 is a horizontal 20 section, line 3—3, Fig. 2.

In the drawings, A is a pail or bucket having a bail-handle A², and all as usual, or otherwise suitable and proper for holding garbage, &c.

25 B is the cabinet to contain the garbage holding pail A. This cabinet is in the general form of a cylindrical chamber having a circular running side-wall B², a bottom or floor-wall B³, attached to said side wall and a 30 removable cover or lid B⁴, suitable to tightly fit and close the upper open end of the side-wall of the cabinet. The cabinet B is of suitable size to receive and hold the garbage pail A, leaving it free and unobstructed at its sides 35 and top.

B⁵ is a chamber, within the side-wall B² and the floor B³, and continuous as to each of said walls.

C, C are sections of wicking or such like, 40 each suspended at its upper-portion from the side-wall of and within the chamber B⁵ at its upper end-portion, and severally preferably extended around said wall and entered into the floor portion of said chamber B⁵.

45 D, D are openings, preferably screened with wire netting, at the inner portion of the chambered side-wall and communicating with the chamber B⁵. These screened openings are in upper and lower rows about the side-wall. The chamber B⁵ is to be properly

charged with liquid disinfectant of any suitable kind, by pouring it thereinto through one of its said openings D. The wicking of the chamber B⁵ draws up the liquid disinfectant and presents it for its gases to escape 55 at the openings D, D, into the chamber of the cabinet, wherein is placed the garbage pail, for action on the garbage, to disinfect it and destroy its obnoxious gases, or in other words, 60 to neutralize them.

The cover B⁴ of the cabinet has a chamber B⁶, the floor B⁷ of which has a number of perforations a, suitably arranged to register with correspondingly arranged perforations b of a disk E located to be oscillated back and forth 65 on a fixed center pin d of and over the cover floor B⁷ and so to have its perforations registered or placed out of register with the perforations a of said floor.

F is a handle to the perforated disk and 70 projected through a slot F² of the cover, in position to be handled to suitably manipulate said disk, and said slot is of suitable length to insure the aforesaid registering and un-registering of said perforations.

75 The chamber of the cover is charged with a pulverized disinfectant, of any suitable kind, and this disinfectant, by oscillating the perforated disk, is sifted onto the garbage in the pail, to the end of disinfecting it, acting 80 in co-operation with the vapors from the liquid disinfectant as before explained. The outer edge of the cover is turned up, so as with the side-wall of the cabinet, the cover being in place, to form a channel or receptacle G for water to seal the joint between the cover and cabinet.

Having thus described my invention, what I claim, and desire to secure by Letters Patent, is—

90 1. In a cabinet B, side and floor-walls B², B³, having a chamber B⁵, wicking C suspended at the upper portion of said chamber, and openings D, in said side-wall, in combination with a cover B⁴ closing, and a pail or bucket 95 A located in said cabinet, substantially as described, for the purposes specified.

2. In a cabinet B, side and floor-walls B², B³, having a chamber B⁵, wicking C suspended at the upper portion of said chamber, and 100

openings D in said side-wall, in combination with a cover B⁴, closing said cabinet and having a chamber B⁶ with a perforated floor B⁷, an oscillating perforated disk E to register and unregister with said perforated floor B⁷, and a pail or bucket located in said cabinet, substantially as described, for the purposes specified.

In testimony whereof I have hereunto set my hand in the presence of two subscribing ^{to} witnesses.

A. R. MIRANDA.
